UNITED STATES PATENT OFFICE

97,180

DESIGN FOR A SHOE

Ernest C. Doring, Quincy, Mass., assignor to
Scholnick Shoe Co., Jamaica Plain, Mass., a
corporation of Massachusetts

Application January 19, 1935, Serial No. 54,925

Term of patent 3½ years

To all whom it may concern:

Be it known that I, Ernest C. Doring, a citizen of the United States, residing at Quincy, in the county of Norfolk and Commonwealth of Massachusetts, have invented a new, original, and ornamental Design for a Shoe, of which the following is a specification, reference being had to the accompanying drawing forming a part thereof, in which

Fig. 1 is a view in side elevation of a shoe showing my new design; and

Fig. 2 is a plan view of the forepart of the shoe.

The ornamental effect of my design resides in a figured strip arranged in a curve across the toe of the shoe and converging in width to a

point at the sole line on both sides of the shoe, combined with a strip of similar appearance extending rearwardly and upwardly in a curve from the sole line at a point near the heel breast and terminated in the counter portion of the shoe a substantial distance in front of the back seam. Both sides of the shoe present the same appearance.

I claim:

The ornamental design for a shoe substantially as shown and described.

In testimony whereof, I have affixed my signature hereto.

ERNEST C. DORING.
